(57) **CLAIM**

The ornamental design for a playing surface for spinning top toy, as shown and described.

DESCRIPTION

FIG. 1 is a front perspective view of a playing surface for spinning top toy, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a perspective view of its split state thereof; and,
FIG. 10 is an enlarged detail view of area 10 in FIG. 1.
The dash-dot-dash broken lines encircling the enlarged views are for annotative purposes only and form no part of the claim thereof.
